UNITED STATES PATENT OFFICE.

FREDERICK P. DROWNE, OF WARREN, RHODE ISLAND.

TOOTH-BRUSH.

No 845,064.

Specification of Letters Patent.

Patented Feb. 26, 1907.

Application filed October 26, 1906. Serial No. 340,720.

To all whom it may concern:

Be it known that I, FREDERICK P. DROWNE, a citizen of the United States of America, and a resident of Warren, in the county of 5 Bristol and State of Rhode Island, have invented certain new and useful Improvements in Tooth-Brushes, of which the following is a specification.

My invention relates to improvements in 10 tooth-brushes, and more particularly to separable tooth-brushes—that is, brushes in which the head or bristle-carrying portion is detachably secured to the handle member.

The object I have in view is to provide 15 brushes of the class referred to with improved simple and inexpensive means whereby the head portion may be easily and quickly detached from the handle when desired and as readily secured to it, the general form and 20 appearance of the brush being substantially the same as the usual integral or one-piece brushes.

To that end my invention consists, essentially, of a handle member having a forked 25 shaped metal extension, a brush-head adapted to receive said extension, and means for readily detachably securing said members together.

In carrying out my invention I propose or 30 prefer to use a handle made of gold, silver, or other suitable metal or combination of metals, the same being made light and ornamental as may be desired. The back of the brush-head may be made of bone, ivory, or 35 other suitable non-metallic material and having a short rearwardly-extending shank arranged to receive the corresponding portion of the handle and being to a certain extent adapted to interlock therewith, the other or 40 forked extension of the handle being at the same time in frictional engagement with the brush-head, thereby preventing the latter from turning and also from being accidentally detached from the handle.

45 By means of the invention one handle may be used with a number of interchangeable brush-heads varying in size, form, &c.

In the accompanying sheet of drawings, 50 Figure 1 represents a side elevation of a tooth-brush embodying my present invention. Fig. 2 is a corresponding plan or top view. Fig. 3 is a plan view showing the handle member detached from the brush-head. Fig. 4 is a side elevation of the brush-head itself. Fig. 5 is a longitudinal sectional view, in enlarged scale, taken on line 5 5 of Fig. 2.

Fig. 6 is an enlarged cross-section taken on line 6 6 of Fig. 1. Fig. 7 is a plan view showing a slightly-modified form of the head portion of the tooth-brush. Fig. 8 is a corresponding transverse sectional view, enlarged, taken on line 8 8 of Fig. 7; and Fig. 9 is a plan view showing a modification of the extension or forked portion of the handle.

In my improved tooth-brush A the head portion *a* is provided with bristles *m* in any well-known way. The back *a'* itself may be made of bone or other suitable material or substance and is provided with a short shank arranged to be detachably secured to the 70 handle *b*, about to be described.

The last-named or handle member may be made of metal and provided with a thin fork-like extension *c*, suitably soldered or otherwise secured to the handle or even being integral with it. In most cases, however, I prefer to make the part *c* of steel, thereby securing a greater degree of strength and resiliency with reduced weight and cost. In order to prevent oxidation, the connection or coupling member *c* may be nickel-plated. The handle itself may be made of silver and shaped in dies, so as to form a hollow member and having suitable ornamentation, if desirable. As drawn, the connecting 85 medium consists of a pair of laterally-separated resilient parallel elongated prongs *c'*, adapted to be inserted in oppositely-disposed longitudinal grooves or openings *a²*, formed in the side edges of the back *a'* of the brush-head. The rear end of the shank portion of said back is cut away to form a flat deep transverse groove *a⁴* between the projecting upper and lower members *a³* and *a⁵* thereof, as clearly represented in Fig. 4. It will be 90 seen that the said grooves *a²* communicate with the groove *a⁴*, the form and arrangement of the same being the counterpart of and adapted to snugly fit the corresponding part of the thin metal extension or coupling 95 member of the handle.

In order to more securely fasten the brush-head and handle members together, the thin connection *c* may have a pin *p* fixed therein, the same extending upwardly a short distance and arranged to enter a hole *p'*, formed in the under side of the said shank member *a³*. (See Fig. 5.)

In lieu of forming the longitudinal grooves *a²* in the back portion of the brush-head for the reception of the prongs *c'* the back may be provided with similarly-spaced round

holes to receive correspondingly - shaped prongs, as indicated at a^2 in Figs. 7 and 8. The prongs may be "set" so as to produce a slight normal convergence toward each other, as represented in Fig. 3.

Assuming the members comprising my improved tooth-brush to have been made substantially as represented in the drawings, the manner of assembling the same may be described as follows: The free ends of the prongs c' of the coupling member c , rigidly secured to the handle b , are introduced into and pressed endwise in the openings or grooves a^2 of the back a' until the metal uniting the base of the prongs is arrested in the bottom of the groove or cut-away portion a^4 of the brush-head's shank, at which instant, owing partly to the slight flexibility of the coupling, the short pin p snaps into the hole p' , thereby locking the parts together and completing the operation, the brush then being ready for use, substantially as represented in Figs. 1 and 2.

The free ends of the prongs may be bent inwardly, as represented at c^2 , Fig. 9. When thus arranged, the said bent portions automatically spring into position partly around and snugly engage the front end of the brush-head at the instant the head and handle members are normally coupled together. In this case the pin p may be dispensed with, the connection or union of the parts being maintained by friction alone.

As hereinbefore stated, I do not claim, broadly, as my invention a tooth - brush having a separable or detachable handle. Brushes embodying my improvement, however, possess advantages over others of this class.

40 What I claim as my invention, and desire to secure by United States Letters Patent, is—

1. As an improved article of manufacture a separable tooth - brush comprising the bristle-carrying head having the back member thereof provided with laterally-separated oppositely-disposed longitudinally-extending openings, and a handle member having its forward portion fork-shaped and adapted to be inserted in said openings and normally held therein by the frictional contact of said members.

2. As an improved article of manufacture,

a separable tooth-brush consisting of the longitudinally-apertured bristle - carrying head provided with a short shank, a handle member having a fork - shaped extension frictionally seated in the apertures of and supporting said head member, and means located in said shank and the adjacent part of the handle for detachably securing the head and handle members together.

3. As an improved article of manufacture, a brush-head having longitudinally-disposed openings and a shank portion provided with a transverse opening communicating with said longitudinal openings adapted to receive the forward portion of a handle therein.

4. In a separable tooth-brush, the combination with a handle member and the brush-head having a short rearwardly-extending shank, of a resilient fork-shaped member in frictional engagement with the said brush-head and shank and rigidly secured to the front end portion of said handle and forming an extension thereof, constructed and arranged substantially as hereinbefore described.

5. In a separable tooth-brush, the combination with the brush-head and its handle member, of a thin metal coupling member rigidly secured to and forming a continuation of said handle and being in frictional engagement with the brush-head whereby said parts are detachably secured together, and a pin fixed to said coupling and extending into the shank portion of the said head, substantially as described and for the purpose set forth.

6. The combination, in a separable tooth-brush, of the bristle-carrying head member having a pair of longitudinal oppositely-disposed parallel grooves formed therein, and a handle member having its forward portion provided with a thin slightly resilient bifurcated or fork-like extension adapted to be inserted into said grooves of the brush-head and frictionally retained therein, substantially as described.

Signed at Providence, Rhode Island, this 100
4th day of October, 1906.

FREDERICK P. DROWNE.
